MACHINE FOR MAKING FILAMENT SUPPORTING STRUCTURES

Alexander Koenig, Berlin-Charlottenburg, Germany, assignor to General Electric Company, a corporation of New York,

Application April 11, 1936, Serial No. 73,369
In Germany June 17, 1935

9 Claims. (Cl. 176—4)

My invention relates to machines for making the filament supporting structure of tubular lamps and the like. My invention relates particularly to the making of a filament supporting structure comprising a stay wire or rod which is to lie longitudinally in the lamp bulb, a lateral support or stay attached thereto for holding and bracing the longitudinal stay in position in the bulb and support wires which are attached to the longitudinal stay at intervals by insulating beads for supporting the filament.

According to my invention, the machine comprises means for advancing and positioning the stay which is preferably unwound from a spool and mechanisms located at spaced intervals along the path of travel of said stay for making and attaching lateral stays, insulating beads and support wires thereto. Features of my machine are the automatic mechanism for making the lateral support or stay, the mechanism for welding it to the longitudinal stay and the mechanism for making and attaching the insulating beads to said longitudinal stay.

Other features and advantages of my invention will appear from the following detailed description of a species thereof and from the accompanying drawings.

In the drawings Fig. 1 is a schematic side elevation of the machine of my invention; Fig. 2 is a vertical section through the lateral stay making and attaching mechanism; Fig. 3 is a side elevation of the stay beading mechanism; Fig. 4 is a plan view of a portion thereof; and Figs. 5 and 6 are side and perspective views of the support wire inserting mechanism.

As shown in Fig. 1 of the drawings, the stay 10 of the filament supporting structure is formed from the wire 10' contained on spool 11. The spool 11 is mounted on the right side of the machine and the wire 10' is withdrawn and carried in a substantially horizontal position to the left through the separate mechanisms of the machine. Upon leaving the spool 11 the wire 10' passes into the lateral stay making and attaching mechanism A, between the jaws of the wire supporting and advancing apparatus B and in operative relation to the beading and support wire inserting mechanisms C and D respectively in turn. The wire 10 is advanced intermittently in such a manner that the same portions thereof coming into position before the lateral stay attaching mechanism A also come into position before each of the other mechanisms in turn.

The lateral support or stay 13 as shown in Figs.

1 and 2, is formed from a wire 13' which is wound on the supply spool 14 and is withdrawn therefrom by rotation of the rollers 15 and 16 which engage the end thereof. The rollers 15 and 16 are mounted on pins 17 and 18 respectively which are pivoted in bracket 19 and which are turned at the same rate by mechanism (not shown). Because of the larger diameter of roller 15, the peripheral speeds of the rollers 15 and 16 differ and the stay wire 13' curls upward and passes through the aperture 20 in plate 21 and between the anvil portion 22 of bracket 19 and the die 23. A groove is provided in the die 23 for the stay wire 13' so that it is properly directed. In this position the end of the stay wire 13' is firmly held between the anvil 22 and die 23 and lies with a mid-portion over the electrode 24 and the stay wire 10 which is located in a groove therein. The end of the stay wire 13' is now severed from the rest by movement of the knife 25 across the face of plate 21 and over the aperture 20. The plate 21 is mounted on a stationary part of the machine 26 and the knife 25 which slides thereon is fastened to the block 27. The block 27 is actuated by lever 28 which has the upper end thereof located in an aperture therein and which is operated through engagement of the bolt 29 in the lower end with the cam 30. The lever 28 is pivoted on the pin 31 and is normally held back against the stop 32 by the spring 33 which extends between it and a stationary part of the machine. The cam 30 is mounted on shaft 34 which in this particular instance turns once between every other indexing movement which results in a lateral stay 13 being attached to the stay 10 at intervals equal to two of the indexing movements. The lateral stay 13 formed by the end of the wire severed from wire 13' is now welded to the stay 10 by downward movement of electrode 35 into contact with said lateral stay 13 at a point above where said stays 10 and 13 contact each other. The electrodes 24 and 35 are connected through wires 36 and 37 in an electrical welding circuit. The electrode 35 and the die 23 are lifted and the stay 10 is indexed longitudinally. The die 23 is turned about pin 38 by mechanism (not shown) so that the lateral stay 13 is removed from the groove therein.

The free end of the stay 10 extending beyond the lateral stay making and attaching mechanism A is located in arm 39 of the stay indexing mechanism B. The arm 39 is provided with jaws which grip the stay 10 during the indexing movement in which the arm 39 and the slide 55

40 on which it is mounted are moved to the left. The slide 40 is mounted in ways 41 in a stationary part of the machine and is operated in one direction by mechanism (not shown) engaging 5 studs 42 therein and in the other direction by the weight 43. The weight 43 is connected through the cord 44 which passes over pulley 45 to the slide 40. The slide 40 indexes the stay 10 to the left and then returns before again repeating the indexing movement.

Further along the path of travel of the stay 10 and at a point at which the joined stays 10 and 13 come to rest between indexing movements is located the beading mechanism C shown in 15 Figs. 1 and 3. The mechanism C supports an insulating rod 46 of glass in this instance which is carried into contact with the stay 10 at the joint between stays 10 and 13. The major portion of the glass rod 46 lies in the passage 47 in the holder 48 and is gripped by the bolt 49 which is located in a passage therein. As shown in Fig. 4, the rod 46 passes through an aperture 50 in the bolt 49 and is gripped between the end of said aperture 50 and the holder 48 (Fig. 3) 20 by movement of said bolt 49 resulting from expansion of the spring 51. The rod 46 is carried into contact with the stay 10 by rotation of the holder 48 about pin 52 as the high part of cam 53 is rotated from engagement with the holder 30 48. The weight of the holder 48 and apparatus attached thereto causes it to swing against the cam 53. The flames from the burners 54 and 55 strike the end of the rod 46 and fuse it to the stays 10 and 13 whereupon the rod 46 and holder 35 48 are moved upward and then to one side to cause the rod 46 to string out and be melted off just above the stay 10. As shown, the glass melted from the rod 46 forms a bead 56 located around the joint between stays 10 and 13 and 40 has a larger quantity of glass below the joint so that the end of a support wire can be inserted therein without touching either of the stays 10 or 13. The rod 46 and holder 48 are moved upward by the arm 57 which is attached to said 45 holder 48 by pin 52 and which is turned about pin 58 by the cam 59 which it engages. The holder 48 is moved sideward by cam 53 which is like cam 59 fastened to shaft 60 which in turn is driven by means (not shown). The pin 58 is mounted in a stationary part 61 of the machine. The outward swing of the holder 48 carries the 50 end of bolt 49 against the stop 63 which pushes said bolt inward releasing the glass rod 46 and allowing it to fall by its own weight against the rest 64. The stay 10 is now indexed once whereupon the holder 48 is moved to the left and down to again bring the rod 46 in contact with the stay 10. With this cycle of movement the beads 56 are placed on the stay 10 twice as often as the 55 lateral stays 13, i. e., at each joint between the stays 10 and 13 and at a point mid-way between.

The next indexing of the stay 10, as shown in Figs. 1 and 5, brings the beaded portion of said stay 10 into operative relation to the support wire inserting mechanism D. Mechanisms for this purpose are well known in the art and may for instance, as shown in Fig. 6, comprise the supply spool 65 with the wire 66 extending therefrom threaded up through an aperture in block 67 and 65 between the jaws 68 and 69. The knife 70 in cooperation with the block 67 severs the end of the wire 66 held by the jaws 68 and 69 from the rest and the peg 71 engages the lower end of the support 72 thus formed and winds it into an 70 open loop 73. The jaws 68 and 69 are then

5 moved upward plunging the upper end of the support 72 into the bead 56 and after releasing said support 72, drop down and grip the end of the wire 66. Additional heat may be used to soften the bead 56 if desired. The jaw 68 is fastened to the arm 74 extending from the slide 75 whereas jaw 69 is pivoted on the pin 76 held by said arm 74. The jaws 68 and 69 are moved vertically by mechanism (not shown) which moves the slide 75 on the stationary ways 77. A 10 spring 78 located in the lower end of each of the jaws 68 and 69 causes said jaws to close and a lever 79 (only partially shown) opens the jaws by striking the lower end of jaw 69. The stay 10 is supported adjacent the inserting mechanism by the rest 80 which is moved up into position after each index of the stay 10. The rest 80 is slidably mounted in a stationary portion 81 of the machine and when in position has the collar 82 against said portion and the stay 10 20 resting in a groove therein.

The stay 10 being of indefinite length permits the machine to be operated indefinitely without a stop and the filament supporting structures to be cut from the resultant structure to the desired 25 length.

What I claim as new and desire to secure by Letters Patent of the United States is:

1. In a device of the class described, the combination of an apparatus for supporting a stay; 30 mechanism located adjacent thereto for making and attaching a second stay to the first stay comprising a pair of rollers turned at different peripheral speeds for curling and feeding an end portion of a wire longitudinally, a knife for severing the curled end portion of said wire from the remainder to form the second stay, a pair of electrodes connected to a welding circuit for welding the second stay to the first stay and mechanisms also located adjacent said apparatus for fusing a bead of insulating material to said first stay and for inserting an end of a support in said bead.

2. In a device of the class described, the combination of apparatus for supporting and moving a stay intermittently in the direction of its longitudinal axis; mechanism located adjacent the path of movement of said stay for feeding and attaching a second stay to said first stay comprising a pair of rollers turned at different peripheral speeds for curling and feeding an end portion of a wire longitudinally, a knife for severing the curled end portion of said wire from the remainder to form the second stay, a pair of electrodes connected to a welding circuit for welding the second stay to the first stay; mechanism located at another position along the path of movement of the first stay for attaching an insulating bead thereto; and mechanism further along said path of movement for inserting a support in said bead.

3. In a device of the class described, the combination of apparatus for supporting a stay and mechanisms located adjacent thereto for feeding and for attaching a second stay to the first stay, for feeding a portion of a rod of insulating material into engagement with the stay, for heating said portion of said rod to fuse it thereto, for moving the unheated portion of said rod away from the fused portion to separate 70 said portions and for inserting a support into said fused portion of the rod on said stay.

4. In a device of the class described, the combination of apparatus for supporting and moving a stay intermittently in the direction of its 75

longitudinal axis; mechanism located adjacent to the path of movement of said stay for making and attaching a second stay to the first comprising a pair of rollers turned at different peripheral speeds for curling and feeding an end portion of a wire longitudinally, a knife for severing said curled end portion of said wire from the remainder to form the second stay, a pair of electrodes connected to a welding circuit for welding the second stay to the first; mechanism located at another position along the path of movement of the first stay for feeding a portion of a rod of insulating material into engagement with the first stay, for heating said portion of said rod to fuse it thereto, for moving the unheated portion of said rod away from the fused portion to separate said portions; and mechanism further along the path of movement of the stay for inserting a support into said fused portion of the rod on said stay.

5. In a device of the class described, means for intermittently feeding a stay wire longitudinally, means for feeding a support wire transversely across said stay wire, means for securing said support wire to said stay wire, means for fusing a bead of vitreous material to said stay wire and means for feeding a filament support wire toward said bead to embed an end thereof in said bead.

30. 6. In a device of the class described, means for intermittently feeding a stay wire longitudinally, a spool for wire, means for feeding wire from said spool transversely of said stay wire and for bending the end of said wire across 35 said stay wire, means for severing said end of said wire, means for securing said end of said wire to said stay wire to form a transverse support, means for fusing a bead of vitreous material to said stay wire and means for feeding a filament support wire toward said bead to embed an end thereof in said bead.

40. 7. In a device of the class described, an electrode, means for feeding a stay wire longitudinally across the face of said electrode, a guide member adjacent to said electrode having a curved groove extending laterally of the path of travel of said stay wire on each side of said electrode, a spool for wire, means for feeding

wire from said spool into said groove in said guide member to bend the end thereof across the face of said electrode by a pushing operation, means for severing said end of said wire, a second electrode disposed adjacent said first-mentioned electrode, and means for moving said second-mentioned electrode toward said first-mentioned electrode to weld said end of said wire to said stay wire to form a transverse support.

45. 8. In a device of the class described, an electrode, means for feeding a stay wire longitudinally across the face of said electrode, a guide member adjacent to said electrode having a curved groove extending laterally of the path of travel of said stay wire on each side of said electrode, a spool for wire, a pair of rollers disposed adjacent to said guide member and adapted to be rotated to feed the wire from said spool therebetween, one of said rollers being larger in diameter than the other so as to curl the end of said wire and guide it into said groove in said guide member to bend the end thereof across the face of said electrode, means for severing said end of said wire, a second electrode disposed adjacent said first-mentioned electrode, and means for moving said second-mentioned electrode toward said first-mentioned electrode to weld said end of said wire to said stay wire to form a transverse support.

50. 9. In a device of the class described, means for feeding a stay wire longitudinally, a holder for supporting a glass rod vertically above said stay wire with its lower end adjacent to said stay wire, means for clamping said glass rod in said holder, heating means for fusing said lower end of said glass rod to form a bead on said stay wire, a rest member located adjacent to said holder, means for swinging said holder to a position above said rest member, means for causing said clamping means to release said glass rod to permit it to drop down in its holder against said rest member and means for swinging said holder back to position the end of the glass rod adjacent to another portion of said stay wire.

ALEXANDER KOENIG.
